UNITED STATES PATENT OFFICE.

CHARLES H. LITTLE, OF EAST CLEVELAND, OHIO.

SCALE.

1,274,293.

Specification of Letters Patent. Patented July 30, 1918.

Application filed February 21, 1916. Serial No. 79,493.

To all whom it may concern:

Be it known that I, CHARLES H. LITTLE, a citizen of the United States, residing at East Cleveland, in the county of Cuyahoga and State of Ohio, have invented a certain new and useful Improvement in Scales, of which the following is a full, clear, and exact description.

This invention relates to scales and rulers, 10 and particularly to metal scales and rulers.

The invention has particular utility also in circular scales or protractors.

It is customary to provide wooden rulers with celluloid strips in which graduations 15 and designating characters are cut, so that the ruler can be easily read, the strips of celluloid being cemented to the ruler body. On the other hand, metal rulers and scales usually have graduations and characters cut 20 directly in the metal, for while it is recognized that it would be desirable to provide graduations in celluloid applied to the metal body this is not done because the shrinking tendency of celluloid precludes it being ef- 25 fectively cemented to the metal. Celluloid undergoes a constant shrinkage, and the stresses due to this shrinkage are so great that no known cement can withstand the shrinking tendency of the celluloid, the re-

30 sult being that in time the cemented strip pulls itself loose from the metal. Not only has it been found impossible to permanently secure celluloid strips to metal by cementing, but as far as I am aware no other successful 35 method has been devised, the inevitable result having been that the celluloid in time pulls itself away from the metal and becomes loosened or warps out of shape, causing the ruler to be rendered worthless or its 40 accuracy to be destroyed.

In consequence, although metal rulers and scales have numerous advantages over those formed of wood, among which might be mentioned the non-warping quality of the 45 former, nevertheless metal rulers and scales have not been used to any great extent except in special cases where metal is required, because of the fact that they are difficult to read, especially in poor light, and even in 50 good light they cause a strain on the eyes of the user.

By the present invention I am enabled to effectively and permanently apply a celluloid strip to a metal scale or ruler body 55 without danger of the strip becoming loose

at any point and without liability of the accuracy of the tool being destroyed or adversely affected. In other words, I am enabled to attach or anchor a strip such as celluloid to the metal body in a manner 60 such that the shrinking tendency of the celluloid is entirely overcome or at least rendered ineffective for destroying the accuracy of the device.

In one of its aspects the invention relates 65 to or has particular utility in circular scales or protractors in which, due to the particular shape of the metal body and the manner in which the non-metallic strip is applied and held thereto, the shrinking action of 70 the strip if formed of celluloid or other material having like properties tends to increase rather than decrease the binding or holding action between the strip and metal. Other features of my invention, while of 75 importance in circular scales or protractors, may be used to advantage in straight metal rulers.

The invention may be briefly summarized 80 as consisting in certain novel details of construction and combinations and arrangements of parts which will be described in the specification and set forth in the appended claims.

In the accompanying sheet of drawings 85 wherein I have shown several embodiments of my invention applied to protractors, Figure 1 is a top plan view of the protractor; Fig. 2 is a transverse sectional view on an enlarged scale through some point of the 90 protractor such for example as along the line 2—2 of Fig. 1; Fig. 3 is a similar view showing a modification; Fig. 4 is a perspective view of a portion of the protractor showing a further modification; and Fig. 5 95 is a view showing on a much enlarged scale the perforations in the base to which the celluloid is applied and the manner in which the perforations are filled with the celluloid.

The scale or protractor includes a metal 100 body 10 which as here shown is in the form of a circle, and in cross-section is substantially in the form of an I or I-beam. It is not essential that the body 10 be in the form of a complete circle as the same results are 105 obtained if the body is slightly less than a full circle or annulus, the latter being the form in which the invention has been embodied with success.

This body 10 is preferably punched or cut 110

from flat metal into the circular shape and the arc-shaped strip or annulus thus formed is then provided on both sides with slots or grooves 10^a and 10^b, leaving at the inner 5 periphery of the strip or body an enlargement or rim 10^c, at its outer periphery a substantially similar enlargement or rim 10^d, and a connecting web or relatively thin base 10^e for the celluloid strip. This provides a 10 protractor body which is not heavy and at the same time it has sufficient strength to easily avoid deformation due to the shrinking tendency of the celluloid strip even though the latter is provided simply on one 15 part or one side of the body.

The upper groove or slot 10^a receives a non-metallic strip 11 preferably of celluloid along the inner marginal portion of which are cut the scale graduations. It is 20 important that the inner marginal edge of the strip 11 engage the shoulder 10^c formed at the inner marginal edge of the groove 10^a when the strip is first placed in the groove, and while the strip preferably fills 25 the entire groove, it is not so essential that it tightly engage at its outer marginal edge the outer peripheral part of the groove, for the reason that the shrinkage of the strip has a tendency to contract the strip and to 30 cause it to bind all the more firmly against the shoulder 10^c. This shoulder is preferably slightly undercut, as shown in Figs. 2, 3 and 4, while at the outer periphery of 35 the groove the strip 11 and metal body 10 are dove-tailed, as shown at 10^e, the groove 10^a having a reentrant groove or slot which receives a relatively thin flange provided at the outer peripheral edge of the strip.

With the above construction wherein the 40 celluloid strip is embedded or inlaid in the circular groove with the inner edge of the strip bearing against the shoulder formed at the inner peripheral edge of the groove, and with the graduations provided at the 45 inner periphery of the strip next to said shoulder, the shrinkage stresses of the celluloid do not affect the accuracy of the instrument nor distort or warp the strip. Additionally, if desired, the strip may be 50 cemented in the groove of the metal body. The use of cement or other fastening means such as hereafter specified is not essential to the invention for the mechanical holding 55 means produced by the circular shoulder which the inner edge of the strip tightly engages has been found very satisfactory in practice. A satisfactory cement which I have used is celluloid dissolved in a suitable solvent such as acetone. The cement 60 could not be relied on in a straight ruler to hold the strip in place, as before explained, but can be advantageously employed in the construction above described for the reason that the shrinkage stresses 65 at any point of the circular celluloid strip

act substantially radially so that the tendency of the shrinkage is to cause the strip to bind all the more firmly against the shoulder against which the inner edge of the strip bears. This shoulder, of course, 70 resists inward contraction of the strip, so that the cement is largely relieved of the shrinking stresses. In consequence, the strip not only stays in position in the groove but its accuracy is never destroyed or 75 adversely affected due to the fact that the graduations are at the inner peripheral portion of the strip which is held by the shoulder against contraction or deformation.

Instead of or in addition to the cement I 80 may employ other methods of anchoring the strip to the metal body which are efficient and may be efficiently employed in straight as well as circular scales or protractors. One expedient which I have employed to 85 advantage consists in positively interlocking the strip and metal in the base of the groove at uniformly distributed points throughout the length and breadth of the strip, and the preferred way of doing this 90 is to provide small numerous closely spaced perforations and to cause the inner surface of the strip to embed itself in and fill these perforations. This is shown in Fig. 3 95 wherein the base or web 10^e is provided with perforations 10^h which are filled with the celluloid. The celluloid can be forced down into these perforations so as to tightly fill the same by warming the strip before it is placed in the protractor or ruler and 100 then by applying pressure onto the strip. This provides an exceedingly effective anchoring means between the strip and metal body and this is true particularly if the web is punched from its lower side. The 105 tendency of the punch or punches is to provide perforations which are somewhat larger at the bottom of the web than at the top surface and to leave a bur projecting up from the upper surface of the web, 110 as is illustrated in the exaggerated or very much enlarged view of Fig. 5. In consequence, when the strip is in position on the metal body with the perforations filled with the celluloid each celluloid filler or plug 115 has at its lower end an enlarged head which cannot easily be pulled through the perforation.

It is not essential that the perforations be provided directly in the base or web 10^e of the body 10, for I find that a separate perforated metal anchor strip 12 placed in the slot or groove receiving the non-metallic or celluloid strip 11 can be employed as shown in Fig. 4. This metal strip may be 120 attached to the celluloid strip 11 before the two are placed in the groove of the body 10 or the metal strip may be placed in the groove and secured therein before the celluloid strip is applied and anchored thereto. 130

If desired, the perforated strip 12 may be embedded in the celluloid strip or fastened between two sheets of celluloid, in which event the celluloid of both strips will fill 5 the perforations.

With both the constructions shown in Figs. 3 and 4 the celluloid strip and perforated web 10^e or perforated metal strip 12 may be cemented together. By cementing 10 the parts as well as interlocking them in the manner shown in Figs. 3 and 4, the celluloid strip is all the more securely fastened in position.

Having thus described my invention, what

15 I claim is:—

1. In a device of the character described, a metal body having a circular groove and a shoulder at the inner periphery of the groove, and a non-metallic strip bearing 20 graduations seated in said groove and having its inner edge bearing against said shoulder.

2. In a device of the character described, a metal body having an arcuate groove with 25 a shoulder at its inner periphery and a celluloid strip bearing graduations held in said groove with its inner edge bearing against the shoulder.

3. In a device of the character described, 30 a metal body having a circular or arcuate groove with a shoulder at its inner periphery and a non-metallic strip bearing graduations secured at its under surface to the base of the groove and at its inner edge bearing 35 against the shoulder.

4. In a device of the character described, a metal body having a circular groove with a shoulder at its inner edge or periphery, a celluloid strip in said groove and having 40 its inner edge bearing against said shoulder, said strip having its inner portion next to said shoulder provided with graduations.

5. In a device of the character described, a metal body provided with a circular shoulder, a circular celluloid strip bearing 45 graduations carried by said body and having its inner edge bearing against said shoulder.

6. In a device of the character described, a metal body having a pair of concentric 50 circular shoulders, a circular celluloid strip carried by said body between said shoulders

and at its inner edge bearing against the inner shoulder.

7. In a scale or ruler, a celluloid strip bearing graduations, and a metal base to 55 which the strip is attached, the base being provided with perforations filled with celluloid.

8. In a metal scale or ruler body, a graduated celluloid strip attached to said metal body, the adjacent surface of the base and 60 strip being interlocked by sockets or perforations in one and projections in the other extending into or filling the sockets or perforations.

9. A scale or ruler having a metal body 65 provided with a pair of shoulders, a graduated celluloid strip attached to the body between the shoulders, the engaging surfaces of the strip and body at distributed points having interfitting parts which anchor the 70 strip to the body.

10. In a scale or ruler, a metal body having a circular shoulder, a graduated celluloid strip attached to said body and having an inner circular edge bearing against the 75 shoulder, the strip and metal body being fastened together at numerous closely spaced points by one part having sockets or perforations filled by the material of the other member. 80

11. In a scale or ruler, a metal body having a circular groove with an abrupt shoulder at the inner periphery thereof, a circular graduated celluloid strip in said groove and having its inner edge bearing against 85 said shoulder, the base of the groove having sockets filled with the celluloid of the strip.

12. In a scale, a metal body having a graduated celluloid strip and having means 90 for mechanically holding the strip against independent shrinkage.

13. In a protractor, a metal body having an annular graduated celluloid strip and having means for mechanically holding the strip against 95 independent shrinkage, said strip having the graduations provided along its inner periphery.

In testimony whereof, I hereunto affix my signature.

CHARLES H. LITTLE.
